UNITED STATES PATENT OFFICE.

JESSE ALEXANDER, OF BROOKLYN, NEW YORK, ASSIGNOR OF ONE-HALF TO GEORGE W. POTTER, OF BROOKLYN, NEW YORK.

TYPE-WRITING-MACHINE RIBBON FEEDING AND OPERATING MECHANISM.

1,163,580.

Specification of Letters Patent.

Patented Dec. 7, 1915.

Application filed November 13, 1914. Serial No. 871,880.

To all whom it may concern:

Be it known that I, JESSE ALEXANDER, a citizen of the United States of America, and residing at New York, in the county of 5 Kings and State of New York, have invented new and useful Improvements in Type-Writing-Machine Ribbon Feeding and Operating Mechanism, of which the following is a specification.

10 The objects of my invention are to simplify and generally improve the ribbon feeding mechanism.

In accordance with these objects I propose to provide driving mechanism at only 15 one of the two spool shafts of the machine and to impart the requisite movement to the other spool shaft by a simple form of driving connection from the first spool shaft. This eliminates one of the customary sets of 20 driving mechanisms for both the spool shafts, reducing the number of parts and lightening the action.

The driving of the first spool shaft is accomplished herein by providing it with a 25 ratchet wheel which is fast on the shaft and is arranged to be engaged by a driving pawl operated from the action of the machine, and the drive to the other spool shaft is effected by providing a reversely operating ratchet 30 loosely engaged on the first shaft and connected by a belt or similar endless connection with the second shaft. The direction of ribbon feed is thus dependent upon which one of the ratchets is being operated. Ordinarily there will be a separate drive pawl for 35 each ratchet and the direction of ribbon feed will be controlled by the disengagement of one pawl and the engagement of the other pawl in respect to the ratchets.

40 Various other features will appear as the specification proceeds.

The accompanying drawings illustrate in concrete form a practical embodiment of my invention, but it will be understood that various changes and modifications may be made 45 without departing from the spirit and scope of the invention and it will furthermore be understood that the terms employed herein are terms of description rather than of limitation, except as may be required by the prior art.

Figure 1, is a vertical sectional view through the central portion of a typewriter constructed in accordance with and embodying the invention. Fig. 2, is an enlarged de-

tail view in plan and with parts broken away and in section, of the driving mechanism. Fig. 3, is a detail view of one of the stirrups on the shift rod, broken away to show the pawl supported thereby. Fig. 4, is a horizontal sectional view taken substantially on the plane of the line 4—4 of Fig. 1. Fig. 5, is a front view of the machine with the frame in section and various parts removed to more clearly disclose the ribbon feed mechanism. 60

In the drawings, the frame of the machine is designated 7, and this, it will be understood may be of any suitable approved construction. The key and type bar action also will be of any approved construction, 70 preferably such as disclosed in my copending application Serial No. 871,879 of even date herewith consisting in a general way of the key levers 8, pivoted type bars 9 and intermediate links 10 pivotally connecting 75 the key levers and type bars.

The ribbon, designated 11, is wound on the two spools 12 and 13 in the usual manner, and these spools are engaged on the upper ends of the spool shafts 14 and 15. These 80 shafts are journaled in suitable bearings 16 at their upper ends and at their lower ends are shown as stepped in the bearing lugs 17. The first spool shaft (14) carries two ratchet wheels 20 and 21 spaced on the shaft one 85 above the other and provided with teeth facing in opposite directions, as indicated in Fig. 2. The upper ratchet 20 is fast on the shaft and serves when engaged by its drive pawl 22 to transmit a ribbon feeding move- 90 ment to this shaft. The other ratchet 21 is loosely engaged on the shaft as by being carried by a loose sleeve 23 and is arranged to be engaged and operated by a drive pawl 24.

The two drive pawls 22 and 24 are shown 95 as operated by upstanding rocker arms 25 and 26 respectively on the rock shaft 27. This shaft may be journaled in the sides of the frame, as indicated at 28 in Fig. 2 and a rocking motion is imparted thereto in any 100 suitable way, as by providing it with rearwardly extending arms 29 engaged by links 30 connected with the universal bar 31. In the illustration the rock shaft 27 is utilized also to operate the ribbon lift 32, disposed at 105 the back of the segment plate 33 and connected at its lower end to an arm 34 fast on the shaft.

It will be apparent from the foregoing that when the drive pawl 22 is engaged with 110

its ratchet 20, which is fast on the shaft 14, said shaft will be turned and the ribbon will be wound on the spool carried by this shaft, the ribbon feed in this case being toward the 5 left. Ribbon feeding movement in the opposite direction is obtained in the present disclosure by disengaging pawl 22 from its ratchet and engaging pawl 24 with its ratchet 21. This ratchet 21, is, as before 10 described, freely revoluble on the shaft 14 and is connected by suitable driving means with the other spool shaft. Such driving means here take the form of a pulley 36 on the lower end of the ratchet sleeve and a 15 belt 37 connecting said pulley with a pulley 38 on the lower end of the second spool shaft. Consequently the ratchet 21, when in operation, serves through the connections described to impart ribbon feeding 20 movement to the second spool shaft in a direction to feed the ribbon toward the right.

The engagement and disengagement of the driving pawls are effected by any suitable means, such means here taking the form of 25 a shift rod 40 carrying abutments to position the pawls in respect to their ratchets. These abutments are shown as stirrups 41 and 42 in which the pawls are slidably engaged and supported (Fig. 3). The spacing of these 30 stirrups on the shift rod is such that in one position of the rod, one pawl will be engaged and the other disengaged from its ratchet and in the other position of the shift rod, the first pawl will be disengaged and the 35 second pawl will be engaged with its ratchet. The shift rod is provided at its outer extended end with a handle or button 43 and a spring 44 engaging in notches 45 in the rod, or other means of a similar nature may be 40 provided for holding the rod in either of its shifted positions.

The escapement mechanism may be of any suitable construction, that shown consisting of a toothed escapement rocker 50, engaging with a rack 51 on the carriage 52 and operated by a link 53 connected with the universal bar. A spring 54 maintains the rocker in its normal position and this spring also will serve to hold the universal bar, 45 rock shaft 27 and connected parts in their 50 normal position of rest.

The ribbon feed mechanism of this invention will be seen to be extremely simple and inexpensive of construction and by the reduction of the number of the parts and other 55

simplification a much lighter touch and speed of action is obtained.

What I claim is:—

1. In a typewriter ribbon feed, ribbon spool shafts, reversely facing ratchet wheels 60 on one of said spool shafts, one of said ratchets being fast and the other being loose on said shaft, pulleys on the respective spool shafts, the pulley on said ratchet shaft being loosely engaged on said shaft 65 but fixed to the loose ratchet thereon so as to rotate therewith and the pulley on the other shaft being fixed thereto, a belt traversing said pulleys, driving pawls arranged for engagement with the respective ratchet 70 wheels and means controlling engagement and disengagement of the pawls in respect to their respective ratchet wheels.

2. In a typewriter ribbon feed, a frame, a typewriting action mounted therein, a pair 75 of upright ribbon spool shafts journaled in the frame, a ratchet wheel fast on one of said shafts, a reversely facing ratchet wheel loosely engaged on said shaft, a rock shaft operated from the typewriting action, rocker 80 arms on said rock shaft, pawls connected to said rocker arms and operated thereby, a displaceable shift rod, means on said shift rod engaging the pawls to carry said pawls upon shifting of the rod, one into engagement and 85 the other out of engagement with its respective ratchet wheel, and a driving connection from the loose ratchet wheel aforesaid to the other spool shaft.

3. In a typewriter ribbon feed, a frame, a 90 typewriting action mounted therein, a pair of upright ribbon spool shafts journaled in the frame, a ratchet wheel fast on one of said shafts, a reversely facing ratchet wheel 95 loosely engaged on said shaft, a rock shaft operated from the typewriting action, rocker arms on said rock shaft, pawls connected to said rocker arms and operated thereby, a displaceable shift rod, stirrups on said shift rod supporting the pawls, the one engaged and 100 the other disengaged from its ratchet wheel, means for holding the shift rod in either of its shifted positions, and a driving connection from the loose ratchet wheel aforesaid to the other spool shaft.

JESSE ALEXANDER.
